[57] CLAIM

The ornamental design for a 110/220 volt receptacle, as shown and described.

DESCRIPTION

FIG. 1 is a front, top and side perspective view of the 110/220 volt receptacle showing our new design in the disassembled condition;

FIG. 2 is a front elevational view thereof;

FIG. 3 is a rear elevational view thereof;

FIG. 4 is a side elevational view of the 110/220 volt receptacle shown in the assembled condition, the opposite side being a mirror image of the side shown in FIG. 4; and,

FIG. 5 is a top plan view thereof, the bottom view being a mirror image of the top view shown in FIG. 5.

FIG. 2

FIG. 3

FIG. 4
